(57) **CLAIM**

I claim the ornamental design for a radio and compact disc player, as shown and described.

DESCRIPTION

FIG. 1 is a perspective view of the radio and compact disc player of the present invention;

FIG. 2 is a front view of the radio and compact disc player;

FIG. 3 is a back view of the radio and compact disc player;

FIG. 4 is a top view of the radio and compact disc player;

FIG. 5 is a bottom view of the radio and compact disc player;

FIG. 6 is a right side of the radio and compact disc player; and,

FIG. 7 is a left side view of the radio and compact disc player.

The broken line showing in the drawing disclosure is for illustrative purposes only and forms no part of the claimed design.
